PRESSER FOOT FOR SEWING MACHINES

Filed Oct. 10, 1927

UNITED STATES PATENT OFFICE

WALTER M. HANNEMAN, OF OAK PARK, ILLINOIS, ASSIGNOR TO UNION SPECIAL MACHINE COMPANY, OF CHICAGO, ILLINOIS, A CORPORATION OF ILLINOIS

PRESSER FOOT FOR SEWING MACHINES

Application filed October 10, 1927. Serial No. 225,260.

The invention relates to new and useful improvements in a presser foot for sewing machines, and more particularly to a presser foot for forming a fell seam.

An object of the invention is to provide a presser foot having a channel extending lengthwise thereof for guiding the fabric sections for felling, with bodily yielding devices for engaging the enchain'd needle thread loops directly in rear of the needles for holding the thread loops during chaining.

In the drawings which show by way of illustration one embodiment of the invention—
15 Figure 1 is a longitudinal sectional view through a presser foot, the throat plate and feed dog associated therewith, and showing a portion of the needles and of the loopers;
Fig. 2 is a view partly in section and partly 20 in plan of the presser foot;

Fig. 3 is a bottom plan view;

Fig. 4 is a sectional view on the line 4—4;

Fig. 5 is a view showing more or less dia- 25 grammatically and in section, the position of the chaining device when the fabric section is entering beneath the foot, and

Fig. 6 is a view similar to Fig. 5, but showing the fabric section as passing from underneath the foot.

30 The invention is directed broadly to a presser foot for forming a felling seam, and a foot portion provided with a channel on its under face, which guides and holds in proper position relative to each other, the interfolded portions of the fabric which are 35 being stitched to form the seam. This channel preferably gradually decreases in depth from the front of the foot toward the rear. Located directly in rear of the needle openings through the foot portion are devices 40 which yield bodily, and these devices are capable of movement to a position slightly below the lower face of the foot portion so as to engage the enchain'd thread loops for 45 clamping the same against the throat plate so as to insure proper stitch formation. These yielding devices pass beneath the surface of the presser foot for clamping and holding the enchain'd thread loops at the time when the 50 fabric section is entering beneath the foot,

and at a time when the fabric section is passing from beneath the foot. They are also located in the channel and extend beneath the upper wall thereof so as to clamp the enchain'd thread loops when no fabric is passing through and the machine is chaining off. These devices yield when the seam is being formed and passing through the guiding channel, at which time they rest upon the upper face of the fabric sections.

Referring more in detail to the drawing, the improved presser foot includes a supporting shank 1 which is adapted to be attached to a presser bar 2. The shank 1 has a forwardly projecting portion 3 to which the foot portion 4 is pivotally attached. Said foot portion is joined to the shank portion 3 by a pivot pin 5 (see Fig. 1). The foot portion extends upwardly alongside of the shank portion 3 as indicated in dotted lines in Fig. 1. The upper face of the foot portion directly beneath the shank portion 3 engages said shank portion and limits the upward movement of the heel of the foot portion. The front end or toe of the foot portion may, however, rise when a fabric section is inserted beneath the foot. This tilting of the foot portion is of the usual operation in a felling presser foot. The foot portion 4 is provided with a guiding channel 6 which extends from the forward end of the foot to the rear end of the foot. This guiding channel is of a width corresponding to the width of the fell seam, that is, the fabric sections are interfolded and guided into the channel, and the edge of the fold in one section engages one wall of the channel, while the edge of the fold in the other section is directly beneath the other side wall of the channel. This channel decreases in depth from the front end of the foot to the rear of the foot, as is usual in a felling foot.

The interfolded fabric sections are secured by a stitching mechanism which consists preferably of two needles 7 and 8. A looper 9 cooperates with the needle 7, and a looper 10 cooperates with the needle 8, and thus it is that two independent parallel lines of stitching are formed. The material is supported on a work support which is provided with a throat plate 11. This throat plate

has the usual feed slots formed therein, and is also provided with a solid portion 12 directly in rear of the needles. The needles are arranged in a line inclined to the line of feed, and therefore, one needle, as viewed in Fig. 1, appears to be in front of the other. Each solid portion 12 is the same distance from its respective needle. The material is fed beneath the presser foot by a feed dog 13 which is of the usual construction.

The invention is directed particularly to the devices which cooperate in holding the enchain thread loops when the machine is chaining and in stitching fabric sections. There is a yielding clamping device 14 associated with each needle. The shank portion 3 is provided with openings in which these clamping devices are located. The clamping devices are similar in construction and a description of one will answer for the other. The clamping device 14 consists of an elongated member placed in vertical position and extending through the recess therefor in the shank portion 3, and also through the opening in the foot portion 4. This clamping device 14 is rigidly attached at its upper end to a spring arm 16 by means of a clamping screw 17. The two spring arms 16, 16 for the clamping devices are preferably formed integral with a supporting shank member 18 which is clamped by means of a screw 19 to the shank 1 of the presser foot. These spring arms normally force the clamping devices in a downward direction, and their extent of downward movement is limited by the spring arm coming in contact with the upper face of the shank portion 3. Each clamping device is rounded off at the lower front side thereof as indicated at 20. Each of the clamping devices 14 is relatively short in the direction of feed being even of less length than the solid section of the throat plate 12. When the material being stitched passes the needle this yielding section will almost immediately engage the enchain thread loops, while the remainder of the presser foot is held raised from the throat plate by the material being stitched passing beneath the same. This enables the threads to be controlled during the chaining between stitched articles from the time when one article passes the needle until the next article is fed thereto.

The operation of the device is thought to be obvious from the above description. Let us assume that the machine is stitching and fabric sections are inserted in the machine. The interfolded portions of the fabric sections are directed into the channel 6. As the fabric sections enter beneath the foot they will tilt the foot, as indicated in Fig. 5. The clamping devices at this time will be moved down through the opening in the presser foot and bear against the enchain thread loops indicated at 21, clamping the same

against the solid portion 12 with which the clamping device is associated. This insures a perfect stitch formation, and the drawing down of the enchain thread loops. The enchain thread loops are fed along by the feed dog cooperating with the presser foot for this purpose. When the fabric section passes the needles and reaches the clamping devices, the rounded forward portions of the clamping devices will pass up on to the fabric section and the yielding devices will then be raised so that their under faces are flush with the upper wall of the channel. The fabric section has reached a point where the thread loops pass through the fabric, and therefore, it is no longer necessary to clamp the thread loops by the clamping devices. The passing of the thread loops through the fabric will hold the thread loops so that proper stitch formation can be accomplished. When the fabric section passes the clamping devices as it moves out from underneath the presser foot, then the clamping device will again move down so as to clamp the enchain thread loops against the solid portion 12 with which it is associated, and this insures proper formation of enchain thread loops. By the improved device described, it will be apparent that fabric sections may be passed in succession beneath the presser foot forming felling seams therein, and a perfect series of enchain thread loops formed extending from one fabric section to another.

It is obvious that minor changes in the details of construction and the arrangement of the parts may be made without departing from the spirit of the invention as set forth in the appended claims.

Having thus described the invention, what I claim as new and desire to secure by Letters Patent is—

1. A presser foot for felling comprising a supporting shank, a foot portion pivoted to said shank, said foot portion having a needle opening therethrough, and a channel in its under face extending longitudinally thereof so as to receive and guide the interfolded portions of the fell seam, and a bodily yielding clamping device disposed directly and wholly in rear of the needle opening and adapted to cooperate with the solid portion of the throat plate for clamping the enchain thread loops during chaining between articles being stitched, said clamping device being relatively short in the direction of feed so as to engage the enchain thread loops and maintain a substantially continuous control of the same when the stitched article is passing from the machine.

2. A presser foot for felling comprising a supporting shank, a foot portion pivoted to said shank, said foot portion having a needle opening therethrough and a channel in its under face extending longitudinally thereof so as to receive and guide the interfolded

portions of the fell seam, a vertically disposed clamping member located directly and wholly in rear of the needle opening, and a yielding arm attached to said member for supporting the same and normally forcing said member so that the lower end thereof projects beneath the foot portion of the presser foot whereby said clamping member is adapted to cooperate with the solid portion of the throat plate for clamping en-chained thread loops during stitching, said clamping member being relatively short in the direction of feed so as to engage the en-chaining thread loops and maintain a substantially continuous control of the same when the stitched article is passing from the machine.

3. A presser foot for felling comprising a supporting shank, a foot portion pivoted to said shank, said foot portion having a needle opening therethrough and a channel in its under face extending longitudinally thereof so as to receive and guide the interfolded portions of the fell seam, a vertically disposed clamping member located directly and wholly in rear of the needle opening, and a yielding arm attached to said member for supporting the same and normally forcing said member so that the lower end thereof projects beneath the foot portion of the presser foot whereby said clamping member is adapted to cooperate with the solid portion of the throat plate for clamping en-chained thread loops during stitching, the forward end of said clamping member being rounded off so as to cause said clamping member to be raised by the fabric section as it passes beneath the presser foot, said clamping member being relatively short in the direction of feed so as to engage the en-chaining thread loops and maintain a substantially continuous control of the same when the stitched article is passing from the machine.

45 In testimony whereof, I affix my signature.
WALTER M. HANNEMAN.
